DENTAL CHAIR

Robert A. Olsen, Palatine, Ill., assignor to American Hospital Supply Corporation, Evanston, Ill.

Filed Aug. 24, 1970, Ser. No. 24,676

Term of patent 14 years

Int. Cl. D6—02

U.S. Cl. D15—3

FIG. 1

FIG. 2

FIG. 3

FIG. 4

FIG. 1 is a side elevational view of a dental chair embodying the design, the opposite side of the chair being substantially identical in appearance;

FIG. 2 is a top plan view of the chair;

FIG. 3 is a front elevational view;

FIG. 4 is a rear elevational view wherein a portion of the base has been omitted for convenience of illustration.

I claim:

The ornamental design for a dental chair, substantially as shown and described.
